UNITED STATES PATENT OFFICE.

CHARLES C. SPREEN, OF DETROIT, MICHIGAN, ASSIGNOR TO ELECTRIC REFRIGERATION CORPORATION, OF DETROIT, MICHIGAN, A CORPORATION OF MICHIGAN.

MECHANICAL REFRIGERATION.

Application filed January 7, 1927. Serial No. 159,625.

My invention relates to mechanical refrigeration, and particularly to adjustable means for supporting an expander in compartments of various sizes in refrigerator cabinets, and the principal object of my invention is to provide new and improved means of this type. In the drawings accompanying this specification and forming a part of this application I have shown, for purposes of illustration, two forms which my invention may assume, and in these drawings:

Figure 1 is a sectional elevation of one embodiment of my invention,

Figure 2 is a horizontal section on the line 15 2—2 of Figure 1, while

Figures 3 and 4 are similar views showing a second embodiment which my invention may assume.

The embodiment of my invention shown in Figures 1 and 2 comprises a refrigerator cabinet 11 having a refrigerating compartment 12 housing an expander 13 held therein by a support 14 which consists of two similar L-shaped plates 15 attached to the side walls of the door aperture 16 of the refrigerating compartment 12 by screws 17.

Associated with the plates 15 in overlapping relation is an additional plate 18 which is adjustably connected to the free ends of the plates 15 by means of bolts 19 passing through registering slots 20 carried by the several plates.

The plate 18 has a centrally disposed aperture 21 which engages over one end of the expander 13. The assembled plates 15 and 17 therefore serve as the sole support for maintaining the expander 13 in the compartment 12.

By making the plates with adjustable connections therebetween the support 14 is adapted to be used in compartments and with expanders of various sizes.

The embodiment of my invention shown in Figures 3 and 4 comprises a pair of L-shaped plates 22 and 23. One end of the plate 22 is attached to the top wall of the door aperture 24 while one end of the plate 23 is attached to the bottom wall thereof. The free ends of the plates 22 and 23 overlap and are adjustably connected together by the bolts 25 adapted to be disposed in slots 26 and apertures 27 in the overlapping plates 22 and 23, respectively. An aperture 28 in the plate 22 engages over one end of the expander 13 whereby the latter is supported.

From the above disclosure it will be obvious to those skilled in the art that I have provided adjustable means for supporting expanders in the refrigerating compartments of refrigerator cabinets.

It will also be obvious to those skilled in the art that the embodiments of my invention herein shown and described may be variously changed and modified without departing from the spirit of my invention or sacrificing the advantages thereof, and it therefore will be understood that the disclosure herein is illustrative only, and that my invention is not limited thereto.

I claim:

1. In a mechanical refrigerator, comprising a refrigerator cabinet provided with a compartment, with an opening affording access to said compartment, and with a door for closing said opening: means for supporting an expander within said compartment, comprising a plate, means for attaching said plate laterally of said opening, and means associated with said plate for engaging said expander for supporting it within said compartment.

2. In a mechanical refrigerator, comprising a refrigerator cabinet provided with a compartment, with an opening affording access to said compartment, and with a door for closing said opening: means for supporting an expander within said compartment, comprising a plate composed of adjustably connected sections, means for attaching said plate laterally of said opening, and means associated with said plate for engaging said expander for supporting it within said compartment.

3. In a mechanical refrigerator, comprising a refrigerator cabinet provided with a compartment, with an opening affording access to said compartment, and with a door for closing said opening: means for supporting an expander within said compartment, comprising a plate having an aperture for engaging said expander for supporting it within said compartment, and means for attaching said plate laterally of said opening.

4. In a mechanical refrigerator, comprising a refrigerator cabinet provided with a compartment, with an opening affording access to said compartment, and with a door for closing said opening: means for supporting an expander within said compartment, comprising a plate composed of adjustably con-

- nected sections and having an aperture for engaging said expander for supporting it within said compartment, and means for attaching said plate laterally of said opening.
5. In a mechanical refrigerator, comprising a refrigerator cabinet provided with a compartment, with an opening affording access to said compartment, and with a door for closing said opening: means for supporting an expander within said compartment, comprising a plate, means for securing said plate to opposite sides of said opening, and means associated with said plate for engaging said expander for supporting it within said compartment.
10. In a mechanical refrigerator, comprising a refrigerator cabinet provided with a compartment, with an opening affording access to said compartment, and with a door for closing said opening: means for supporting an expander within said compartment, comprising a plate, flanges for attaching said plate to the walls of said opening, and means associated with said plate for engaging said expander for supporting it within said compartment.
15. In a mechanical refrigerator, comprising a refrigerator cabinet provided with a compartment, with an opening affording access to said compartment, and with a door for closing said opening: means for support-

ing an expander within said compartment, comprising a plate, flanges for attaching said plate laterally of said opening, and means associated with said plate for engaging said expander for supporting it within said compartment. 25

7. In a mechanical refrigerator, comprising a refrigerator cabinet provided with a compartment, with an opening affording access to said compartment, and with a door for closing said opening: means for supporting an expander within said compartment, comprising a plate, flanges for attaching said plate to the walls of said opening, and means associated with said plate for engaging said expander for supporting it within said compartment. 30

In testimony whereof I hereunto affix my signature.

CHARLES C. SPREEN.
